UNITED STATES PATENT OFFICE.

WALTER T. FLING, OF ST. JOSEPH, MISSOURI.

FURNACE-BURNER.

No. 895,998.

Specification of Letters Patent.

Patented Aug. 11, 1908.

Application filed September 26, 1907. Serial No. 394,761.

To all whom it may concern:

Be it known that I, WALTER T. FLING, a citizen of the United States, residing at St. Joseph, in the county of Buchanan and State of Missouri, have invented new and useful Improvements in Furnace-Burners, of which the following is a specification.

This invention relates to furnace burners, so called, and designed for the purpose of burning natural gas and heating furnaces.

One of the principal objects of the invention is to provide a sectional burner which can be readily placed within the furnace before the sections are connected together and after the sections have been placed in the furnace they may be quickly connected together to form a substantially circular burner having a series of inlet openings in the under side thereof for natural gas.

Another object of the invention is to provide a burner of the class referred to which shall be simple in construction and efficient in operation.

These and other objects may be attained by means of the construction illustrated in the accompanying drawing, in which:—

Figure 1 is a central vertical section through a furnace burner made in accordance with my invention. Fig. 2 is a perspective view of the upper member or top of the burner. Fig. 3 is a detail section showing the manner of securing the top to the hollow inner ring. Fig. 4 is a perspective view of two sections of the hollow inner ring. Fig. 5 is a similar view of two sections of the base.

Referring to the drawing for a more particular description of my invention, the numeral 1 designates each of the sections of the base of the burner and since these sections are made in duplicate of identical construction a description of one will serve for all. In the present instance there are four of these sections and each consists of a one-fourth sectional plate having upon one end a lug 2 and upon the opposite end an upwardly extending boss 3 for the lug 2 upon the next adjacent plate or section. A grooved bead 4 extends around the inner edge of the section 1. Formed on the under side of the base plate 1 is a boss 5, said boss having an inlet opening 6 therein for the gas. These sec-

tions of the base plate are connected together by suitable bolts 7, which pass through the lugs 2 and through the bosses 3, as will be understood. Supported upon the base are the 55 hollow ring sections 8, said sections each comprising an upper wall provided with a boss 9 through which the attaching screw 10 passes. A downwardly extending inner wall 11 is provided on each section and an outer 60 wall 12 provided with jet openings 13. The lower edge of the wall 11 engages the groove in the bead 4. The top 14 is made in halves and one of said halves is provided with a perforation 15 through which the attaching bolt 65 16 passes. The screws 10 pass through holes 17 in the top. The outer side flanges 18 are provided with outlet openings 19.

From the foregoing it will be obvious that a furnace burner made in accordance with 70 my invention can be set up within a furnace owing to the fact that it is made in sections and the gas will be confined within the burner until it becomes thoroughly heated when the heated gases will escape through the jet 75 openings 13 and out through the outlet openings 19 into the furnace. The current of air which is taken into the burner and mingled with gases serves to force the flame out through the outlet against the walls of the 80 furnace, thus distributing the heat more widely and giving a more intense heat.

Having thus described the invention, what is claimed as new, is:—

A furnace burner comprising a base having 85 a grooved rib, said base being made in sections and provided with means for connecting said sections together, a hollow inner ring made in sections and having an inner wall fitted into said grooved rib and provided 90 with an outer wall having jet openings therein, perforated bosses upon the upper surface of said ring sections and a two part cover provided with means for connecting said parts and an annular outer wall provided with outlet openings.

In testimony whereof I affix my signature in presence of two witnesses.

WALTER T. FLING.
